UNITED STATES PATENT OFFICE

2,033,593

ELECTRIC DEHYDRATOR

Thomas N. St. Hill, San Marino, Calif., assignor
to Petroleum Rectifying Company of California,
Los Angeles, Calif., a corporation of California

Application August 19, 1932, Serial No. 629,412
Renewed July 10, 1935

7 Claims. (Cl. 204—24)

My invention relates to the electric treatment of petroleum emulsions, and more particularly to an improved type of electric treater.

Petroleum as it comes from the well is often associated with minute water droplets and forms a relatively tight water-in-oil emulsion. Before this petroleum can be used commercially the water content must be materially reduced. In the past, oil refineries have considered a reduction in water content to below 3% to be satisfactory, but pipe-line requirements of many refineries now call for oil having no more than a fraction of 1% of water therein.

Many types of existing electric dehydrators will not meet such pipe-line requirements, and it is an important object of the present invention to provide a new type of electric treater utilizing a dual field and which is very effective in removing substantially all of the water from petroleum emulsion.

It is a further object of the invention to provide a treater having a plurality of treating spaces, and to impress a higher potential across certain of these treating spaces than across certain other of these spaces whereby the emulsion is subjected to successively higher potentials.

It is a further object of the invention to provide a novel electrode structure, and preferably to make one portion of this electrode structure rotatable.

Another object of the invention is to provide a novel emulsion introduction system.

Still further objects and advantages of the invention will be made evident to those skilled in the art from the following descriptions of the preferred embodiment of the invention.

In the drawing—

Fig. 1 is a vertical sectional view illustrating the details of the preferred form of the invention.

Fig. 2 is a sectional view taken on the line 2—2 of Fig. 1.

Referring particularly to Fig. 1, I have illustrated a tank 10 including upper and lower heads 11 and 12, this tank being substantially filled with liquid. An intake means 14 extends into the lower end of the tank and is in the form of an intake pipe including an upward extending leg 15. A plurality of nozzles 17 extend outward from an intermediate section of this leg and communicate with the interior thereof. Various types of nozzles may be utilized, but in the preferred embodiment I utilize four pipes suitably secured to the leg 15 and extending outward toward the tank. The outermost ends of these

pipes are bent so as to discharge non-radially with respect to the tank. It is usually preferable to bend the ends of the pipe, as best shown in Fig. 2, so that in effect they discharge in a direction tangential to a circle around the axis of the leg 15. In addition, it is preferable to bend the outer ends of these pipes slightly upward so that they discharge in an inclined direction. Emulsion is forced under pressure through the intake means 14 and is forced through the nozzles 17, being discharged non-radially so as to set the body of liquid in the tank 10 into circulation. The upward inclination of the ends of these nozzles serves to give the incoming emulsion an upward movement so that it rises in the tank 10. Any suitable means may be provided for closing the upper end of the leg 15. In Fig. 1 a plug 20 is shown in this capacity.

The upper end of the leg 15 forms a central electrode 21 and may be enlarged as shown. In other instances such an enlarged electrode is not necessary and this electrode may be of the same diameter as the lower portion of the leg 15.

An insulator 25 is supported by the upper head 11 inside the tank and carries a bearing 26 of the thrust type which in turn rotatably supports a rod 27. An intermediate electrode 30 is fixed to the lower end of the rod 27 so as to rotate therewith, and comprises a flat interstitial electrode 31 preferably formed of screen suitably reinforced so that it is maintained in a horizontal position. The intermediate electrode 30 also includes an electrode means in the form of a plurality of blades or arms 32 depending therefrom and extending between the central electrode 21 and the tank. A lower treating space is thus formed between the central electrode 21 and the depending arms 32, and another treating space is formed between the lower portion of the flat interstitial electrode 31 and the upper end of the electrode 21. These treating spaces have been termed primary or lower treating spaces and respectively indicated by the numerals 34 and 35. Additional treating spaces are formed between the blades 32 and the tank 10 as indicated by the numeral 36, while the edge of the flat interstitial electrode 31 cooperates with the tank 10 in defining still another treating space indicated by the numeral 37.

The final treating action takes place in an upper treating space 38 formed between the flat interstitial electrode 31 and an upper interstitial electrode 40 providing a central opening 41 through which the rod 27 extends. Insulators 45

43 and 44 support this upper interstitial electrode 40 and insulate it from the tank.

It is preferable to establish a potential difference between the electrodes 30 and 40 which is greater than the potential difference between the electrodes 21 and 30. This may be accomplished by any one of a number of means. In Fig. 1, I have shown a pair of transformers 48 and 49 providing secondary windings 50 and 51, one terminal of each being connected together and to the tank 10 as by a conductor 52. The remaining terminal of the secondary winding 50 is connected by a conductor 53 to the upper live electrode 40 through the insulator 44, while the 15 remaining terminal of the secondary winding 51 is connected by a conductor 55 to the intermediate electrode, a bushing 56 being provided to carry the current through the upper head 11. The primary windings of these transformers are 20 connected to a supply line 52. The transformers are connected in additive relation so that the potential between the flat interstitial electrode 31 and the upper electrode 40 will be represented by the sum of the potentials developed by the secondary windings 50 and 51. On the other hand, the potential difference between the tank 10 and either the electrode 30 or 40 is much less than this additive potential, being the potential of only one of the secondary windings. In view of the fact 25 that the electrode 21 is electrically connected to the tank 10, it will be clear that the potentials across the lower treating spaces 34 and 35 will also be less than the potential across the upper treating space 38.

30 In the operation of the device the tank 10 may be preliminarily filled with dry oil. The incoming emulsion discharged from the nozzles 17 will set this body of oil into rotation and the emulsion will rise in the tank and into the treating spaces 34, 35, and 36 wherein it will be subjected to an electric field corresponding in magnitude to the potential developed by the secondary winding 51. In these treating spaces the water droplets of the emulsion are acted upon 35 by the electric field and coalesce into larger masses. Most of these larger masses will drop downward from these treating spaces and into the lower end of the tank 10 where they will form a body of water which can be removed from 40 the tank through a pipe 60. The remaining emulsion constituents move upward in the tank and either move through a more intense field set up in the treating space 37 adjacent the edge of the flat interstitial electrode 31 or move upward 45 through the interstices of the interstitial electrode 31 and thence into the treating space 38. Here the remaining emulsion is subjected to a still more intense electric field and further coalescence is effected, the water droplets moving downward 50 through the interstitial electrode 31 while the dry oil moves upward through the interstitial electrode 40 and is withdrawn from the upper end of the tank through a pipe 61.

55 The tendency of the emulsion to form low resistance paths between the electrodes defining the treating spaces is counteracted by two tendencies. In the first place, it will be clear that the rotation of the liquid in the tank 10 rotates the intermediate electrode 30 at a speed 60 which is only slightly less than the speed of rotation of the liquid in the tank. The arms 32 are preferably shaped in the form of flat plates, as shown in Fig. 2, to increase the force tending to turn the electrode 30. In the second place, 65 any tendency to form low resistance paths across

the treating spaces is minimized by the use of potential sources connected as shown in conjunction with an upper treating space into which only the drier emulsion moves, this drier emulsion having much less tendency to short-circuit the electrodes than the original wet emulsion introduced through the nozzles 17. In addition, leakage currents are minimized by the electrode system shown, for the potential between the tank 10 and either the electrode 30 or electrode 40 is 10 only half the potential effective in treating the emulsion in the upper treating space 38.

15 Such a dual-field system is effective in removing the greater percentage of the water from the emulsion, so that the oil moving through the pipe 61 has a water content which is only a fraction of 1%. One of the important features of the invention is the use of superimposed fields the uppermost of which is of higher potential. Another feature of the invention is the particular 20 electrode structure utilized, and especially the interstitial construction thereof which permits liquid to reach the upper treating space 38 through the interstices thereof. Still another feature of the invention is the novel construction of the distributing means including the nozzles 17, especially in conjunction with the central electrode 21 which is supported thereby.

25 I claim as my invention:

30 1. In an electric treater, the combination of: a tank; an intermediate live electrode in said tank but insulated therefrom and including a flat interstitial electrode; a live upper electrode above said intermediate live electrode and insulated from said tank, said upper and intermediate live electrodes cooperating in bounding an unobstructed upper treating space in which an electric field may be established of a maximum potential determined by the difference in potential of said live electrodes; electrode means 35 below said flat interstitial electrode and cooperating with said intermediate live electrode in defining a lower treating space communicating with said upper treating space through the interstices of said flat interstitial electrode; and potential-supply means electrically connected to said upper and intermediate live electrodes and to said lower electrode means and including a pair of transformer windings connected in additive relation for building up between said upper and intermediate live electrodes bounding said upper treating space a high potential, one of said transformer windings being connected between said lower and said intermediate electrodes to establish therebetween a lower potential.

40 2. In an electric treater, the combination of: a tank; an intermediate live electrode in said tank but insulated therefrom and providing a flat interstitial electrode and a downward extending electrode means depending from said flat 45 interstitial electrode; an upper live electrode above said intermediate live electrode and insulated from said tank and from said intermediate electrode, said upper and intermediate electrodes cooperating in bounding an unobstructed upper treating space in which an electric field may be established of a maximum potential determined by the difference in potential of said live electrodes; a lower electrode cooperating with said downward extending electrode means to define a lower treating space communicating with said upper treating space through the interstices of said flat interstitial electrode; means for introducing the emulsion to be treated into said lower treating space whereby a portion thereof 50

flows upward into said upper treating space; and means for establishing fields in said treating spaces comprising a potential-supply means impressing between said upper and intermediate electrodes bounding said upper treating space a potential difference greater than between said lower electrode and said downward extending electrode means.

3. In an electric treater, the combination of: a pair of electrodes spaced from each other and electrically connected together; an intermediate electrode extending into the space between the electrodes of said pair and insulated therefrom, said pair of electrodes cooperating with said intermediate electrode in defining a primary treating space; an upper electrode above and insulated from said intermediate electrode and cooperating therewith in defining an unobstructed secondary treating space in which an electric field may be established of a maximum potential determined by the difference in potential of said upper and intermediate electrodes and which secondary treating space communicates with the material moving upward from said primary treating space; and means for establishing a potential difference between said upper and intermediate electrodes and a lower potential difference between said intermediate electrode and the electrodes comprising said pair of electrodes whereby the potential across said primary treating space is less than that across said secondary treating space.

4. In an electric treater, the combination of: a tank containing a body of liquid; an intermediate electrode comprising a flat interstitial member and a plurality of arms depending therefrom; means for rotatably mounting said electrode in said tank; a central electrode extending into the space bounded by said intermediate electrode and in spaced relationship with said arms and said flat interstitial member to define a treating space; means for rotating said liquid in said tank whereby said intermediate electrode is turned by contact with said rotating liquid; and means for establishing an electric field between said central electrode and said intermediate electrode whereby the liquid is treated and a portion thereof rises through said flat interstitial member to the upper portion of said tank.

5. In an electric treater, the combination of: an intake pipe providing a leg in the form of a pipe; nozzle means communicating with said leg at an intermediate section between the upper and lower ends thereof, the end of said leg be-

yond said nozzle means comprising an electrode; means for closing said intake pipe at a section above said nozzle means; means for supplying emulsion to be treated to said intake pipe whence it is discharged from said leg through said nozzle means; electrode means around said electrode formed by said leg and cooperating therewith in defining a treating space supplied with emulsion by said nozzles; and means for establishing a potential difference across said treating space. 10

6. In an electric treater, the combination of: a tank containing a body of liquid; an intake pipe providing a leg; a rotatable electrode surrounding said leg, the terminal end of said leg forming an electrode cooperating with said rotatable electrode in defining a treating space; nozzle means supported by said leg and communicating with an intermediate section thereof, said nozzle means supplying emulsion to said treating space and being directed non-radially 20 with respect to said tank to set said body of liquid into rotation whereby said rotatable electrode is rotated; and means for establishing a potential difference between said electrodes to set up an electric field in said treating space. 25

7. In an electric treater, the combination of: a tank containing a body of liquid; an upper interstitial electrode providing a central opening; means for insulating said upper electrode from said tank; a rod extending through said central opening to a point therebelow; an intermediate electrode secured to said rod and providing a flat interstitial electrode with a plurality of arms depending therefrom, said flat interstitial electrode cooperating with said upper interstitial 35 electrode to provide an upper treating space; an intake pipe extending upward in said tank in alignment with said rod, the upper end of said intake pipe providing a central electrode electrically connected to said tank, whereby said 40 arms are positioned between said central electrode and said tank; nozzle means extending into said tank and introducing the emulsion to be treated therein, said nozzle means being directed non-radially with respect to said tank to set said 45 liquid into rotation; means cooperating with said rod for rotatably mounting said intermediate electrode whereby this electrode moves with said rotating body of liquid; and means for establishing a potential difference between said upper and 50 intermediate electrodes and between said tank and said upper and intermediate electrodes.
